UNITED STATES PATENT OFFICE.

CHARLES L. WAGNER, OF BOONTON, NEW JERSEY, ASSIGNOR TO C. L. W. PATENTS CORPORATION, A CORPORATION OF NEW JERSEY.

HEATER.

Application filed March 28, 1925. Serial No. 19,016.

This invention relates to heaters.

In certain industries and for certain processes it is necessary to heat liquors of a corrosive or caustic nature or of an acid nature or content. It is often desirable that this heating take place under pressure. For instance, in the paper and pulp industry caustic soda, lime and magnesia and various salts are used to digest or "cook" the raw material, removing intercellular matter and freeing the fibres to be utilized. This material is subjected to high temperature under high pressures. The common practice has been to inject live steam into the mixture, which dilutes the liquor to be recovered which necessitates a higher concentration of chemicals, due to this dilution, to do the work required to the detriment of the fibre strength. This common practice has been occasioned by the fact that there has been no practical heating device as the conditions under which it must operate are very severe and extremely destructive.

One of the objects of this invention is to provide a heating device for liquors of a corrosive character or caustic or acid nature. Another object is to provide a heater in which the liquids to be heated will not leak into the heating medium. Still another object of this invention is to provide a heater that will be efficient in the operation, particularly with minimum losses of temperature, pressure and velocity.

A further object is to provide a device of long life and one in which any part thereof is readily replaceable.

Referring to the drawings:

Figure 1, is a longitudinal sectional view of a device embodying the principles of my invention.

Figure 2, is a front view of the device showing the head.

Figure 3, is a view of tube plate 3 removed from the device.

Figure 4, is a view of a modified form of device embodying the principles of my invention.

In carrying out my invention I propose to provide a device wherein the component parts have freedom of individual expansion and wherein the flow of the liquid is not impeded by impact losses with consequent loss of efficiency. The conditions of high temperature, relatively high pressure and relatively great velocity make it extremely im-

portant that the dynamic impact losses be obviated since the effect of these are to destroy in a relatively short time any device wherein they prevail. I therefore propose to provide a cylindrical metallic shell 1, having tubes 2 therein through which the liquor is forced. These tubes, in the preferred embodiment thereof (Figure 1), are secured to tube plate 3 by having the rolled ends of tubes 2 inserted through openings in plate 3 and welding the ends to plate 3. Tubes 2 are preferably closed at one end, in other words U shaped, so that only one tube plate is required and the tubes 2 are free to expand and contract. The curvature of the closed ends of tubes 2 should be of such a diameter as to permit of the change of direction of the flow of the liquor without losses. Internally secured to shell 1 are supports 31 upon which rest tubes 2. Tubes 2, however, are not fastened to supports 31 but are free to expand.

The tube plate 3 has a flange 4 which has an exteriorly machined surface to fit within shell 1 to which it is riveted by rivets 5. The joint between flange 4 and shell 1 may be calked. A head 6 is bolted onto tube plate 3 by means of bolts 6'. In order to have tight joints the seating surfaces 7 between head 6 and tube plate 3 are machined and asbestos metallic gaskets 8 are used. Head 6 is of unique construction in that the inner surface is formed into compartments 9 which have curved walls 10 adapted to receive the discharge from each alternate pipe of tubes 2 and direct the liquid into the adjacent pipe of tubes 2. The curved walls 10 of compartments 9 is of such design as to merely change the direction of flow without creating dynamic impact losses. In order to provide proper strengthening for head 6, ribs 11 are cast integral therewith.

The other end of shell 1 has ring 18 secured thereto by rivets 19, the contacting surfaces are machined and calked to provide a tight joint. Ring 18 carries cover plate 20 to which it is secured by bolts 20'. The bearing surfaces between cover plate 20 and ring 18 are likewise machined and a metallic gasket is used to make the joint steam tight. Brackets 24 support the shell and are bolted to the flooring by bolts 25. Straps 26 pass around shell 1 and are bolted to brackets 24 by bolts 27. Referring to Figures 1 and 3, it will be noted that plate 3 has channel

seats 30 cut therein for the walls of chamber 9 to seat to form slip joints to prevent short circuiting of liquor.

In operation, valves 13 and 16 are opened 5 permitting the liquid to enter through pipe 12, into the lower chamber 9 of header 3, where it passes through the lower row of tubes 2 and back through the second row of tubes into the next adjacent chamber where 10 the liquid is directed back into the next adjacent pipe and so on through the heater and out through outlet pipe 15. The heating medium preferably steam is admitted to the top of the shell 1 through pipe 21. The 15 condensation together with the exhaust steam are withdrawn through pipe 22 leading from the bottom of shell 1 through trap and valve 23. Gage 17 is located in outlet pipe 15 to indicate the liquid pressure and 20 gage 32' is located at the top of shell 1 to indicate the steam pressure in the heater. When it is desirable to shut down the heater, valves 13 and 16 may be closed and the liquid will then flow through by-pass, 14 upon 25 opening valve 14'.

Modifications in detail may be made in my device and still fall within the scope of my invention.

I have shown one such modification where- 30 in the chambers 9' are formed by blocks that

can be inserted in the header 6' and are not integral therewith. I have also shown a form of baffling 32, 33, to distribute the steam more uniformly throughout the lengths of the coils.

35

What I claim is:—

1. A heater comprising a shell, a header, tubes within said shell to conduct the medium to be heated, the ends of said tubes connected with said header, replaceable 40 blocks within said header, said blocks forming chambers in said header, the walls of said chambers being curved to change the direction of flow of the medium to be heated from one tube to the next adjacent tube. 45

2. A heater comprising a shell, a header, a tube plate, replaceable blocks in said header forming chambers with curved walls, a series of rows of tubes connected to said tube plate to conduct the medium to be heated, said chambers of said replaceable blocks cooperating with said tubes to change the direction of flow from one series of tubes to another series of tubes without impact losses. 50

Signed at New York, in the county of New York and State of New York, this 18th day of March, A. D. 1925.

CHARLES L. WAGNER.
